UNITED STATES PATENT OFFICE.

FRANK M. PRESTWICH, OF NEW YORK, N. Y.

GARMENT.

1,071,955.

Specification of Letters Patent.

Patented Sept. 2, 1913.

Application filed May 16, 1912. Serial No. 697,612.

To all whom it may concern:

Be it known that I, FRANK M. PRESTWICH, a subject of the King of England, and resident of New York, in the county of New York and State of New York, have invented certain new and useful Improvements in Garments, of which the following is a specification.

My invention relates to clothing and is 10 herein illustrated as applied to a man's coat.

It is specifically directed to improving the stiffening or lining of clothes, so that they will hold their shape, and bend without undue creasing.

15 This object I attain by distributing the stiffening in an improved manner. One thickness or grade of stiffening may in a coat extend to the very edge of the front. This preferably is some extremely resilent 20 material such as hair cloth. A greater thickness may extend from the shoulder to the neighborhood of the curve where the lapel turns back and a still greater thickness may extend some distance from the shoulder part 25 way toward the lapel. The stiffening between the lapel turn and the arm hole at the shoulder has one thickness preferably of some solid material not easily bent. Such a material is canvas which has body but not 30 much resiliency. Thus there may be a gradual increase of stiffness from the front edge to the arm hole. The extra stiffness through the shoulder may be extended to the edge of the coat in the vicinity of the lower end of 35 the lapel, and is weakened as it approaches the edge of the coat at that point. In order to conceal the edges of the various stiffenings, said edges may be weakened. This may be done by serrating or perforating 40 these edges.

Other improvements and advantages will be pointed out below or be obvious to those skilled in the art.

In the accompanying drawings Figure 1 45 represents one form of canvas as cut for a coat. Fig. 2 represents a piece of hair cloth which may be placed on it. Fig. 3 represents another form of hair cloth which may cover it, the hair cloth being composed of 50 two pieces which are shown as slightly separated for the sake of clearness. Fig. 4 represents an alternative form showing the whole lining of a coat front assembled.

In Fig. 4, 1 is a piece of canvas covering 55 the whole side of a coat front. This is shown cut out from 2 to 3 for the armhole, and

from the armhole extends a heavy hair cloth stiffener 4 which ends along a nearly vertical line 5, 6, and is serrated along said line as at 7, 7. From this line 5, 6 extends over the front of the coat a thinner hair cloth 8, which ends in the neighborhood of the place where the fold of the lapel will come from 9 to 10. This cloth is serrated along the edge 5, 6 so as to fit in between 60 the serrations of the stiffener 4, and is also serrated along the line 9, 10 as seen at 11, 11 to break the stiffness of the edge. This line 9, 10 is preferably a hollow curve so as to weaken the hair cloth where it extends 70 out to the edge of the canvas at 9. The lapel itself is stiffened with canvas only as seen at 12.

In Fig. 1 is shown a canvas 13 which resembles the canvas 1 except that it extends only to the neighborhood of the lapel the fold of which would lie along the line 14, 15. This edge may be weakened by being perforated as at 23, or serrated as at 16, 16. The serrations instead of extending along a 80 curve may have their points extend to about the curve of the lapel along a line joining 14 and 15 and may extend back as far as a line running down from the shoulder at 21 to the bottom 22 of the hair cloth and the 85 serrations increase in depth toward the bottom. Over this canvas may be placed a large piece of hair cloth 17 which extends to the line, 18, 19 forming the edge of the garment itself (shown in dotted line 18, 90 Fig. 1). Preferably, however, I use the hair cloth shown in Fig. 3 which is composed of two pieces like that shown in Fig. 4 except that it extends to the edge of the garment. As will be seen, the hair cloth in 95 Fig. 3 is composed of a light and a heavy portion which are serrated at their junction as are the pieces 4 and 8 of Fig. 4. This is shown in dotted lines in Fig. 1.

It will be noted that near the end of the 100 fold of the lapel there is a double thickness of stiffening, as at 9 in Fig. 4. There is a similar double thickness at 14 in Fig. 1, when either the cloth of Fig. 2 or of Fig. 3 is placed in position on said figure. The 105 edges of the hair cloth are preferably all bound with a narrow binding 20 which elsewhere is omitted for the sake of clearness. And the hair is arranged to run unbroken horizontally preferably. The hair cloth is 110 that usually used for stiffening clothes and the canvas is of the kind used for that work

also. The canvas may be either cotton, linen or other similar material, and such material is usually heavily sized. The lighter hair cloth is preferably what is known in the 5 trade as wool hair cloth. The full shape of the garment front with both hair cloth and canvas is shown by dotted lines extending to 18 in Fig. 1, and this also represents approximately the extent of the body fabric 10 forming the outer surface of the garment. A fragment of the body fabric of the garment is shown at 25 on Fig. 1.

While I have described the various materials as canvas and hair cloth, it will be 15 observed that these are merely typical of fabrics which give increased life and body to the cloth of the garment. From a different point of view they may be called stiffening materials.

20 For the sake of clearness in the drawings, all stitching has been omitted, but it will be understood that the materials are fastened together in any usual manner.

It will be noted that this system of interlining gives a structure which is known as 25 a coat shape retainer though it may be actually used in garments other than coats.

What therefore I claim is.

1. In a coat shape retainer, the combination 30 of a stiffening extending from the arm hole to the front edge, a second stiffening extending from the armhole to the neighborhood of the lapel turn, said second stiffening having its edge adjacent the lapel turn 35 serrated.

2. In a coat shape retainer, the combination 40 with a canvas extending from the arm hole of the coat forward and terminating in the neighborhood of the turn of the lapel of the coat, said canvas covering the whole front of the coat except the lapel, of a stiff-

ening more resilient than said canvas covering the lapel.

3. In a coat shape retainer, the combination 45 with a canvas extending from the arm hole of the coat forward and terminating in the neighborhood of the turn of the lapel of the coat, said canvas covering the whole front of the coat except the lapel, of another stiffening more resilient than said canvas 50 extending from the arm hole across the entire upper part of the coat front so that it covers the lapel.

4. In a coat shape retainer, the combination 55 with a canvas extending from the arm hole of the coat forward and terminating in the neighborhood of the turn of the lapel of the coat, said canvas covering the whole front of the coat except the lapel, of a hair cloth stiffening extending from said arm 60 hole part way across said canvas toward said lapel turn, and another stiffening more resilient than said canvas extending forward from said hair cloth so as to cover the lapel.

5. In a coat shape retainer, the combination 65 with a canvas extending from the arm hole of the coat forward and terminating in the neighborhood of the turn of the lapel of the coat, said canvas covering the whole front of the coat except the lapel, of a heavy 70 hair cloth stiffening extending from said arm hole part way to the lapel turn, and a lighter hair cloth more resilient than said canvas extending forward from said heavy hair cloth so as to cover the lapel. 75

Signed at New York in the county of New York and State of New York this 15th day of May A. D. 1912.

FRANK M. PRESTWICH.
